Specification for Design.

Patented Mar. 31, 1914.

Application filed January 29, 1913. Serial No. 745,014. Term of patent 14 years.

To all whom it may concern:

Be it known that I, JOSEPH WARREN CUTLER, a citizen of the United States, residing at Rochester, in the county of Monroe and State of New York, have invented a new, original, and ornamental Design for Street Letter-Boxes, of which the following is a specification, reference being had to the accompanying drawings, forming a part thereof.

Figure 1 is a front elevation; Fig. 2 is a

side elevation; Fig. 3 is a front elevation of the box or receptacle removed from the standard, and Fig. 4 is a side elevation of the same, showing my new design.

I claim:

The ornamental design for a street letter box as herein shown.

JOSEPH WARREN CUTLER.
